DESIGN FOR A CONTROL COLUMN

Robert E. Bingman, Detroit, Mich., assignor to
Mechanical Handling Systems, Inc., Detroit,
Mich., a corporation of Michigan

Application February 9, 1946, Serial No. 126,405

Term of patent 14 years

(Cl. D26—5)

To all whom it may concern:

Be it known that I, Robert E. Bingman, a citizen of the United States and residing at Detroit, in the county of Wayne and State of Michigan, have invented a new, original, and ornamental Design for a Control Column, of which the following is a specification, reference being had to the accompanying drawing, in which Fig. 1 is a front elevational view of a control column show-

ing my new design, and Fig. 2 is a perspective view thereof.

The characteristic features of my design reside in the portions shown by means of full lines in the drawings.

I claim:

The ornamental design for a control column, as shown and described.

ROBERT E. BINGMAN.
